US0D1005841S

(12) **United States Design Patent** (10) **Patent No.:** **US D1,005,841 S**
(45) **Date of Patent:** **** Nov. 28, 2023**

(54) **CLOSEABLE CARTON**

(71) Applicant: **Inno-Pak, LLC**, Delaware, OH (US)

(72) Inventors: **Jonathan D. Sill**, Delaware, OH (US);
Steven A. Mayer, Indianapolis, IN (US)

(73) Assignee: **Inno-Pak, LLC**, Delaware, OH (US)

(**) Term: **15 Years**

(21) Appl. No.: **29/862,369**

(22) Filed: **Dec. 8, 2022**

Related U.S. Application Data

(60) Division of application No. 29/826,894, filed on Feb. 16, 2022, now Pat. No. Des. 976,101, which is a continuation of application No. 29/762,294, filed on Dec. 15, 2020, now Pat. No. Des. 982,432, which is a division of application No. 29/633,127, filed on Jan. 12, 2018, now Pat. No. Des. 904,871, which is a continuation-in-part of application No. 29/573,421, filed on Aug. 5, 2016, now abandoned, which is a division of application No. 29/539,525, filed on Sep. 15, 2015, now Pat. No. Des. 774,893, which is a continuation of application No. 29/527,085, filed on May 15, 2015, now Pat. No. Des. 762,113, said application No. 29/633,127 is a continuation-in-part of application No. 29/573,599, filed on Aug. 8, 2016, now abandoned, which is a division of application No. 29/545,302, filed on Nov. 11, 2015, now Pat. No. Des. 774,896, which is a continuation-in-part of (Continued)

(57) **CLAIM**

The ornamental design for a closeable carton, as shown and described.

DESCRIPTION

FIG. 1 is a front perspective view of the closeable carton showing another alternate configuration, the rear perspective view being a mirror image;

FIG. 2 is a top plan view thereof;

FIG. 3 is a front perspective view of the closeable carton showing yet another alternate configuration, the rear perspective view being a mirror image;

FIG. 4 is a front elevation view thereof, the rear elevation view being a mirror image; and,

FIG. 5 is a top plan view thereof.

In the drawings, the broken lines are for the purpose of illustrating portions of the closeable carton that form no part of the claimed design.

1 Claim, 5 Drawing Sheets
